DESIGN FOR AN OPTICAL COMPARATOR

Lubbert H. Van Dellen, Pella, Iowa

Application April 29, 1943, Serial No. 110,074

Term of patent 7 years

To all whom it may concern:

Be it known that I, Lubbert H. Van Dellen, a citizen of the United States and a resident of Pella, in the county of Marion and State of Iowa, have invented a new, original, and ornamental Design for an Optical Comparator, of which the following is a specification, reference being had to the accompanying drawing, forming a part thereof.

Figure 1 is a side elevation of an optical com-

parator, showing my design and illustrating the piece holder and operating handle in operative position; and

Figure 2 is a perspective view thereof, showing the piece holder and operating handle in the in-operative position.

I claim:

The ornamental design for an optical comparator, substantially as shown and described.

LUBBERT H. VAN DELLEN.
